UNITED STATES PATENT OFFICE.

WILLIAM H. RAY, OF MONROE, MICHIGAN, ASSIGNOR TO THE WEIS FIBRE CONTAINER CORPORATION, OF MONROE, MICHIGAN, A CORPORATION OF MICHIGAN.

COVER-SEALING MEANS.

1,394,581.

Specification of Letters Patent.

Patented Oct. 25, 1921.

Application filed November 5, 1919. Serial No. 335,790.

To all whom it may concern:

Be it known that I, WILLIAM H. RAY, a citizen of the United States of America, and a resident of Monroe, Michigan, have 5 invented a certain new and useful Improvement in Cover-Sealing Means, of which the following is a specification.

This invention relates to sealing devices for holding in place the cover of a pail or 10 other container.

Generally stated, therefore, the object of the invention is to provide a simple and inexpensive form of sealing means which can be readily applied to hold in place the cover 15 of a pail or other container, and which can be easily broken and removed when it is desired to remove the contents of the container or pail.

Another object is to provide a simple form 20 of sealing means which will not be liable to be broken during shipment of any desired commodity in a container or pail of this character.

It is also an object to provide certain 25 details tending to increase the general efficiency of a cover-sealing means of this particular character.

To these and other useful ends the invention consists in matters hereinafter set 30 forth and claimed and shown in the accompanying drawings, in which—

Figure 1 is a perspective of a pail having the cover thereof held in place by sealing means embodying the principles of the 35 invention.

Fig. 2 is an enlarged detail or fragmentary section.

Fig. 3 is also an enlarged detail or fragmentary section.

As thus illustrated, the container is in the 40 form of a pail having a fiber body 1, the bottom of said body (not shown) being held in place by metal binding 2 in any suitable or desired manner. The bail-shaped 45 handle 3 is secured to the body by means of sheet metal brackets 4 of any suitable character, so that the handle may swing in either direction. For the purposes of the invention, however, the pail may be of any suitable 50 or desired character.

The cover 5 may also be of any suitable character, but is preferably so formed that it will fit down tightly over the top of the pail, thus effectively closing the latter.

The sealing means include a wire 6 which 55 is threaded through the eye 7 of one of the brackets 4, then stretched across the top of the cover and brought down and through the eye 7 of the other bracket 4, it being understood that these two brackets are disposed 60 at opposite sides of the pail. Staples 8 are inserted through the sides of the pail, near the upper edge thereof, each staple having its ends clenched on the inner surface of the pail, and having its outer end provided 65 with a hump 10 which provides an eye for the said wire which forms a part of the sealing means. With this arrangement, said wire, after passing through the second bracket 4, is then stretched at 11 around the 70 outer surface of the pail until it reaches one of the staples 8, and is then brought upward and stretched across the top of the cover. Then the wire is brought downward and through the other staple 8, and the two ends 75 of the wire are brought together and fastened by a lead seal 12, or by any other suitable means. In this way, therefore, the wire extends over the outer side surface of the pail, at opposite sides thereof, and is also 80 held in crossed relation upon the top surface of the cover, whereby the latter is held firmly down in place.

Any desired commodity can be shipped in the pail, and the wire sealing means will 85 hold the cover effectively in place until it is desired to remove the contents. The seal 12 can then be broken, or the wire can be cut, thereby to release the cover. The sealing means, it will be seen, do not interfere with the manipulation of the handle 3 of the pail, as the latter is free to swing in either direction. The brackets 4, however, which form the handle attaching 90 means, serve also as a part of the sealing 95 means.

What I claim as my invention is:—

1. In combination with a container having a removable cover, sealing means comprising wire stretched across the top of the cover, a 100 handle having attaching means therefor, and instrumentalities including said attaching means for connecting the wire to the sides of the container, below the edges of the cover, so that only the wire extends over the cover, and 105 whereby the wire is stretched straight across the cover from one side of the pail to the other.

2. A structure as specified in claim 1, said instrumentalities comprising staples inserted through the sides of the container.

3. A structure as specified in claim 1, said 5 instrumentalities comprising sheet metal brackets secured to the sides of the container, having eyes for the wire, said handle also being connected to the eyes of said brackets.

4. A structure as specified in claim 1, said 10 instrumentalities comprising devices arranged at points on the sides of the container to hold the wire in crossed relation on the upper surface of the cover, and to hold the wire stretched from one device to another at opposite sides of the container, the ends of the 15 wire being fastened together.

5. In a container, the combination of a 20 body forming the sides of a pail, brackets secured to said body at the top thereof, a bail-shaped handle connected to said brackets, metal devices applied to the side of the pail at points between said brackets, a cover for the top of the pail, and a sealing wire threaded through said brackets at points below the 25 top of the pail and through said metal devices and across the top of the cover to hold

the latter in place, so that only the wire extends over the cover.

6. Sealing means for holding in place the 30 cover of a pail or other container, comprising a single sealing wire stretched crosswise over the cover so that each of the two crossed strands extends straight over the cover from one side of the pail to the other, substantially as shown and described, and a handle having 35 attaching means to hold said wire in place.

7. In a pail sealing device, a single wire 40 which is so arranged that by connecting its two ends together it is stretched taut throughout its length, extending crosswise of itself over the top of the pail, and extending along opposite sides of the pail, so that only the wire extends over the top.

8. In a pail sealing device, a single wire 45 which is so arranged that by connecting its two ends together it is stretched taut throughout its length, extending back and forth between four points on the sides of the pail, over the top of the pail, and means at 50 said points to hold the wire in place.

WILLIAM H. RAY.

It is hereby certified that the State of incorporation of the assignee in Letters Patent No. 1,394,581, granted October 25, 1921, upon the application of William H. Ray, of Monroe, Michigan, for an improvement in "Cover-Sealing Means," was erroneously given as "Michigan," whereas said State should have been given as *South Dakota*, as shown by the record of assignments in this office; and that the said Letters Patent should be read with this correction therein that the same may conform to the record of the case in the Patent Office.

Signed and sealed this 13th day of December, A. D., 1921.

[SEAL.]

KARL FENNING,

Acting Commissioner of Patents.
